LLP(57) **CLAIM**

The ornamental design for a retaining ring, as shown and described.

DESCRIPTION

FIG. 1 is a top perspective view of a retaining ring of our invention;

FIG. 2 is a bottom perspective view of the retaining ring of FIG. 1;

FIG. 3 is a top view of the retaining ring of FIG. 1;

FIG. 4 is a front view of the retaining ring of FIG. 3, with the back view being a mirror image thereof;

FIG. 5 is a bottom view of the retaining ring of FIG. 3 shown rotated with the mounting tab at the top and bottom of the retaining ring; and,

FIG. 6 is a front view of the retaining ring of FIG. 5, with the opposing back view being a mirror image thereof.
